UNITED STATES PATENT OFFICE.

ERIK JÖRGENSEN HATT, OF VEJLE, DENMARK.

LOCK.

SPECIFICATION forming part of Letters Patent No. 739,867, dated September 29, 1903.

Application filed November 4, 1901. Serial No. 81,151. (No model.)

To all whom it may concern:

Be it known that I, ERIK JÖRGENSEN HATT, a subject of the King of Denmark, and a resident of Vejle, Denmark, have invented certain new and useful Improvements in Safety-Locks, of which the following is a specification.

The invention relates to safety-locks, and more particularly to that kind of such safety-locks to which belongs a key of particular shape or measurement, so that it is impossible to open the lock with any other key.

The safety-lock according to this invention is provided with notches on the main bolt which abut against a hook or the like if the bit of the key used for the opening of the lock is either too long or too short.

With these ends in view the invention consists in the peculiar combination and in the novel construction, arrangement, and adaptation of parts, all as more fully hereinafter described, shown in the accompanying drawings, and then specifically defined in the appended claim.

In the annexed drawings the construction of the lock is shown.

Figure 1 is a plan view of the lock with the cover-plate removed and the bolt fully projected. Fig. 2 is a similar view with the bolt partly projected. Fig. 3 is a detail view of the key.

The main bolt *a* is provided on upper and lower edges with notches *b* *c*. Above the upper edge of main bolt *a* a hook *d* is movably secured on a pin *e* and arranged in such a manner that its end is pressed against the upper edge of main bolt *a* by a spring *f*, fixed to the lock-case.

A locking-bar *h*, one end of which is movable, connected with hook *d* by means of a bolt *g*, passes behind the main bolt *a* and terminates at the lower edge of the same in a projection or beak *i*. The lower end of the locking-bar *h* is beveled. For the guidance of the locking-bar *h* a bolt-clamp *k* is provided at one side, while the beveled edge of the locking-bar abuts or rests against the beveled edge of a wedge-piece *l*, movably mounted in a support *m* and guided by a pin *n*, projecting through a slot in the wedge-piece

l. In the left-hand side of wedge-piece *l* there is provided an arc-shaped incision *r* as abutment for the short bit *p* of the key, while an aperture *q*, provided in the lower edge of the main bolt *a*, serves for the reception of the long bit *o*.

The safety-lock operates as follows: In the locking position (see Fig. 1 of the drawings) the end of hook *d* is pressed against the upper edge of the main bolt *a* by means of spring *f*. The beveled side of the locking-bar *h* rests on the beveled side of the wedge-piece *l*, and the beak-iron *i* is in such a position that the main bolt *a* may pass freely. If the proper key is used, the short bit *p* presses the wedge-piece *l* upward when the key is turned, whereby the wedge-piece *l*, and with it the head of the locking-bar *h*, is slightly moved to the right, so that the hook *d* is raised from the upper edge of the main bolt *a*, which can be freely opened by the long bit *o* of the key. If, however, a pick-lock or a wrong key is used, the short bit of which is either too long or too short, the safety device immediately enters into operation. With a key the short bit of which is too long the lateral movement of the wedge-piece *l*, and in consequence that of the head of the locking-bar *h*, is exaggerated, so that the beak-iron *i* engages with notch *c* on the lower edge of the main bolt *a* and locks the main bolt, while the wedge-piece *l* will not be moved sufficiently to raise the hook *d* from the upper edge of the main bolt if the short bit of the key is too small, and consequently the notch *b* of the upper edge engages with this hook, and the main bolt is locked again.

What I claim as new, and desire to secure by Letters Patent, is—

A safety-lock comprising in combination, a main bolt *a* with notches *b* and *c* in its upper and lower edges, a hook *d* pivotally connected to the lock-case and tending to bear normally against the upper edge of the main bolt, a locking-bar *h* pivotally connected with the hook *d* and located behind the main bolt and provided at its lower end with a projection or beak *i*, a wedge-piece *l*, the beveled side of which rests against the beveled end of the locking-bar *h*, a support *m* for movably sup-

porting said wedge-piece and having a stud
engaging a slot in the wedge-piece for guid-
ing the same, said wedge-piece having an arc-
shaped recess r , adapted to receive the short
5 bit of a key, the main bolt having a recess q
for the reception of the longer bit of the key,
substantially as described.

In witness whereof I have hereinunto set my
hand in the presence of two witnesses.

ERIK JÖRGENSEN HATT.
